UNITED STATES PATENT OFFICE.

EMIL MAYER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

ARC-LAMP GENERATOR FOR PRODUCING AND AMPLIFYING ELECTRICAL OSCILLATIONS.

Application filed December 5, 1922, Serial No. 605,065, and in Germany December 23, 1921.

An object of the present invention is to provide an arc-lamp arrangement which performs the functions of a cathode relay.

In accordance with the present invention, 5 an arc-lamp is used in which, as in well known arrangements, one of the electrodes is constructed of metal and is cooled by water. However, unlike previous arrangements, the negative characteristic of the arc is not used 10 for generating oscillations by means of an oscillating circuit in parallel connection with the electrodes of the arc, but an incombustible diaphragm is provided in the path of the arc, i. e. between the two electrodes. 15 This diaphragm is used as a controlling element by means of which the current of the arc may be varied in a manner similar to the variation of the current in the output circuit of a cathode relay by its grid. 20 The diaphragm is composed of metal alloy, properly cooled and has one or a plurality of apertures in the path of the arc. By means of this diaphragm the arc may be controlled in accordance with the well 25 known method of controlling cathode tubes by their grids either by applying a potential between the cathode and the diaphragm or by a magnetic field affecting this part of the arc.

30 This arrangement is adapted for high frequency amplification or for generating oscillations.

Let us assume that a high frequency potential of sufficient amplitude is impressed 35 on the cathode and the diaphragm. This same frequency but at an increased amplitude will occur between the cathode and anode. However, in the same manner as with tubes a closed oscillating circuit may 40 be provided between the cathode and the anode and from this circuit high frequency potential may be supplied to the diaphragm (outside energization, auto-energization). If the diaphragm is actuated by a magnetic 45 field instead of a potential then this may be also used in the same manner for controlling the arc.

For the purpose of more readily defining the arc, auxiliary igniting arrangements may

be used in a manner well known in the art 50 of controlled extinguishing sparks.

The single figure of the drawing represents an embodiment of the invention in a circuit arrangement.

As shown, 1, 2 are the solid electrodes of 55 an arc generator which in series with choke coil 3, 4 is connected with the current source. The arc is connected in parallel with a tuning coil 5 and a tuning condenser 6. 7 is the primary coil of a transformer 60 which induces current in the coil 8. The coil 8 is connected through a condenser 9 on one hand with the negative electrode 2 of the arc and on the other hand with the diaphragm 10. The diaphragm 10 which 65 in the well known manner is kept at a low temperature by means of cooling, constitutes the controlling element or grid. Obviously, the coils 7 and 8 may be combined in a single coil or some other well known back- 70 coupling circuit may be used.

Having described my invention, what I claim is:

1. In a device of the character described, 75 an arc lamp having an anode and a solid cathode, both of said electrodes being exposed to the air, and a control electrode for controlling the passage of current between said anode and cathode.

2. In a device of the character described, 80 an arc lamp having an anode and a solid cathode, both of said electrodes being exposed to the air, and a grid for controlling the passage of current between said anode and cathode.

3. In a device of the character described, 85 an arc lamp having an anode and a solid cathode, both of said electrodes being exposed to the air, and a grid in the current path between said anode and cathode for 90 controlling the current flow between said anode and cathode.

4. In an electric system, a device comprising 95 an arc lamp having an anode and a solid cathode, both of said electrodes being exposed to the air, and a control electrode for controlling the passage of current between said anode and cathode, an output and an

input circuit for said device, means for regeneratively coupling said circuits together, and means for maintaining the arc.

5. In an electric system, a device comprising an arc lamp having an anode and a solid cathode, both of said electrodes being exposed to the air, and a control electrode for controlling the passage of current between

said anode and cathode, a first circuit connecting said anode and cathode, a second circuit connecting said control electrode and cathode, means for regeneratively coupling said circuits together, and means for maintaining the arc.

EMIL MAYER.
